UNITED STATES PATENT OFFICE.

EUGENE E. ALEXANDER, OF WOLFE CITY, TEXAS.

COTTON-SACK CARRIAGE.

1,112,963.

Specification of Letters Patent.

Patented Oct. 6, 1914.

Application filed September 23, 1913. Serial No. 791,376.

To all whom it may concern:

Be it known that I, EUGENE E. ALEXANDER, a citizen of the United States, residing at Wolfe City, in the county of Hunt and State of Texas, have invented new and useful Improvements in Cotton-Sack Carriages, of which the following is a specification.

This invention has relation to carriages especially adapted to be used for supporting cotton sacks and it consists in the novel features hereinafter described and claimed.

An object of the invention is to provide a carriage of the character indicated which is of simple structure and which is longitudinally extensible in order to support sacks of different lengths.

With the above object in view the carriage comprises front and rear members supported upon journaled rollers and longitudinally extensible bars connecting the said members together.

In the accompanying drawing:—Figure 1 is a perspective view of the carriage. The other figures are detailed views of the several features thereof.

The carriage includes a front member 1 and a rear member 2. These members are U-shaped in edge elevation and rollers 3 are journaled between the end portions of the said members. Angle pieces 4 are fixed in any suitable manner to the upper corners of the front and rear members and angle pieces 5 are secured to the upper intermediate portions of the said members. Side bars 6 are secured to the angle pieces 4 and extend transversely across the members 1 and 2 and project beyond the forward side of the foremost roller 3 and beyond the rear side of the rearmost roller 3. The said bars 6 are made up of sections which overlap each other at their inner end portions and which are provided with guiding loops 7 the loop of one section receiving the other section and vice versa. The sections of the side bars 6 are freely slideable with relation to each other that is to say no securing devices are provided for holding the said sections in adjusted positions with relation to each other. A bar 8 is connected with the angle pieces 5 and the end portions of the said bar extend transversely across the front and rear pieces 1 and 2 and project beyond the same in a manner similar to that described in connection with the bars 6. The bar 8 is

also made up of sections and the inner end portions of the said sections overlap each other. One of the sections is provided with a longitudinally disposed slot 9 and the other section of the bar 8 is provided with a clamping screw 10 which passes through the slot 9. Therefore it will be seen that the bar 8 is longitudinally extensible and means is provided for holding the sections of the said bar at adjusted positions with relation to each other. The rear sections of the bars 6 and 8 are provided with pivoted hooks 11. Straps 12 are connected with the upper end portions of the foremost angle pieces 4 and carry hooks 13. The cotton sack indicated at 14 is adapted to rest upon the upper edges of the bars 6 and 8 and between the upper end portions of the angle pieces 4 which project somewhat above the upper edges of the side bars 6. A sack 14 is provided with rings 15 which are adapted to be engaged with the hooks 11 and the same sack is further provided with rings 16 which are adapted to be engaged with the hooks 13. When the sack is connected with the hooks as above described the mouth portion of the sack may be used as means for pulling the carriage over the surface of the ground.

In use the sack 14 is connected with the hooks as above described and the carriage is drawn between the rows of standing plants and as the cotton is picked it may be deposited into the sack through the mouth thereof. As the cotton is gathered from the plants the carriage may be moved along the rows and the rollers will prevent the carriage from sinking to any great extent into the soil.

By loosening the clamping screw 10 the sections of the bars 6 and 8 may be adjusted longitudinally with relation to each other to accommodate sacks of different make and when the said sections have been properly adjusted they are held by tightening the clamp screw 10. As the sack is filled the upper projecting end portions of the angle pieces 4 will prevent the sides of the sack from bulging over the side bars 6 and over the ends of the rollers 3.

Therefore it will be seen that a carriage of simple structure is provided and that the arrangement of the parts is such as to effect a strong and durable support for the sack.

Having described the invention what is claimed is:—

A sack carriage comprising front and rear members, supporting members journaled to the first mentioned members, angle bars fixed to the upper outer portions of the first mentioned members, longitudinally extensible bars connected with the said angle members the upper portions of the angle

members at the outer ends of the first mentioned members projecting above the upper edges of the said angle bars.

In testimony whereof I affix my signature in presence of two witnesses.

EUGENE E. ALEXANDER.
